UNITED STATES PATENT OFFICE.

DANIEL B. LUTEN, OF INDIANAPOLIS, INDIANA.

FALSE WORK.

1,106,880.

Specification of Letters Patent.

Patented Aug. 11, 1914.

Original application filed November 1, 1906, Serial No. 341,605. Divided and this application filed May 24, 1912. Serial No. 699,534.

To all whom it may concern:

Be it known that I, DANIEL B. LUTEN, a citizen of the United States, residing at Indianapolis, in the county of Marion and 5 State of Indiana, have invented a new and useful False Work, of which the following is a specification.

My invention relates to improvements in falsework, especially for concrete structures, 10 and has for its purpose to provide a compression member for such falsework that will have great strength without increased cost for materials or labor, and which is specially adapted to be removed in such a 15 manner that there are gradually developed in the structure supported on the falsework the stresses to which such structure is to be subjected.

This application is a division of an application filed by me November 1, 1906, 20 Serial No. 341,605.

The invention is illustrated in the accompanying drawings in which the same reference characters describe like parts throughout the several views.

Figure 1 is an elevation of a false work of my improved type with a superimposed arch of a bridge. Fig. 2 is an axial section of the parts shown in Fig. 1 and at right 30 angles thereto. Fig. 3 is a detail of a portion of the falsework on an enlarged scale, and Fig. 4 is a section on line 4—4 of Fig. 3.

The joists 30 of the falsework, usually 35 covered with a sheeting 30' for forming and holding the concrete or other material of which the proposed structure, such as the arch A, is to be built, are supported upon posts each of which consists of two members 31 and 32 the sum of the individual strengths 40 of which is not enough to support the load applied to the two combined. One member 31 may be secured to the joist 30, as by nails or otherwise, these members being placed upon footings 33. A nailed or other similar 45 joint is somewhat unreliable and after the members 31 are placed on their footings, the other members 32 are therefore preferably fitted under the joists and brought accurately to position and bearing by wedging 50 or otherwise. The member 32 is arranged with relation to the member 31 to form a post substantially T shaped in cross-section, as shown in Fig. 4, and is connected to the member 31 by means which, while in active 55 position, will intimately associate the two

members so that each will strengthen the other but which may be readily brought to a condition giving independence of the two members so that in that independent condition they may separately yield under the 60 same load that had been previously sustained by them.

A very convenient means of connecting the two members is by wires 36 passed around the two members 31 and 32 and having their 65 ends twisted together to hold the two members 31 and 32 securely together causing one to brace the other. The supports are braced by braces 37 all of which, where the falsework is used for bridge construction, lie in a 70 plane substantially parallel with the stream: that is, parallel with the axis of the bridge arch, said brace members being attached to that one of the members of the supporting posts which will, under the applied load, 75 tend to buckle in the direction of the axis of the arch. This construction results in extremely light posts of great strength, placed with minimum of labor, and with secure connections, yet which will serve as an extremely rigid falsework support during the 80 erection of any structure.

After the falsework is completed, the structure for which it is built is constructed on it, such structure being here illustrated 85 as a concrete arch A of a bridge. After this structure is sufficiently set, by selectively cutting wires 36 and withdrawing braces 37 the support of the falsework can be very 90 gradually withdrawn from beneath the completed structure. This withdrawing of the braces 37 makes the various supporting posts independent of each other, and the cutting of the wires 36 resolves into its two elements, 95 31 and 32, the composite supporting post formed by said two elements when they are connected by such wires. The resolution into its elements of the composite supporting post allows the two elements to buckle independently, in transverse directions, with 100 the result that the combined load which the two elements after separation can support is much less than that which the composite post could support before it was resolved into its elements by the cutting of the wires. 105 All this allows the falsework to settle gradually, thereby gradually developing in the arch the stresses to which it is to be subjected.

In erecting such false work the member 31 110

is first nailed flat against the joist 30 and the operation repeated for each post and joist until the line of posts and joists is complete, after which it is set in position in the proposed structure. The member 32 is then wedged under the joist and supports the major part of the load because of its end bearing the joist, the member 31 serving mainly to stiffen 32. Hence the member 31 10 may be made of thinner and wider material as shown by Figs. 1 and 2. As this member will effectually resist buckling of the other member 32 there is therefore, save in exceptional cases, no necessity for sway bracing 15 transverse to the direction of the stream, that is, in line with the joists, when necessary struts 38 may be provided to take care of any horizontal thrusts on the falsework transverse to the arch axis. But the posts 20 may require sway bracing 37 parallel with the flow of the stream, which of course is not objectionable.

I claim:

1. A falsework centering containing compound compression members in series for supporting a load, each compression member consisting of a plurality of pieces each of which has major and minor dimensions transverse to its length, the major dimension 30 of one piece being greater than the major dimension of another piece and being arranged transversely to that major dimension of the other piece and transversely to the series of compression members, and releasable connecting members uniting the pieces of each compression member; and sway bracing uniting the substantially parallel pieces of a plurality of said compression members.

40 2. A falsework centering comprising a joist supported by a compound compression member composed of a plurality of pieces each having major and minor dimensions transverse to its length, the major dimension 45 of one piece being arranged longitudinally of and overlapping the joist and transversely to the major dimension of another piece of the compression member, and a releasable connecting member to unite the 50 pieces of the compression member.

3. A falsework centering comprising a joist supported by a compound compression member composed of a plurality of detachably interconnected pieces, each having major and minor dimensions transverse to its length, the major dimension of one piece being arranged longitudinally of and overlapping the joist and transversely to the major dimension of another piece of the compression member with end bearing against the joist.

4. A falsework centering containing compound compression members for supporting a load and each composed of a plurality of 65 pieces having major and minor dimensions

transverse to their lengths, the major dimension of one piece being arranged transversely to the major dimension of another piece, and a withdrawable connection to unite the pieces of each compression member.

5. A falsework centering for a stream-crossing bridge comprising compound columns for supporting a load and each consisting of a plurality of releasably interconnected longitudinal pieces, one of said pieces being wider than another of said pieces and arranged with its wider dimension transverse to the direction of flow of the stream, and sway bracing attached to said columns and parallel to the direction of flow of the stream.

6. A falsework centering comprising a joist supported by a compound compression member composed of a plurality of releasably interconnected longitudinal pieces, one of said pieces having major and minor dimensions transverse to its length, the major dimension of said piece being arranged longitudinally of and overlapping the joist, and another of said pieces having end bearing against the joist.

7. A falsework centering containing compound compression members for supporting a load, each of which members is composed of two pieces having major and minor dimensions transverse to their lengths, the two pieces being set together so that their combined cross section is approximately T shaped with the cross of the T longer than the stem thereof, a releasable connection between the two pieces, and sway bracing extending between compression members in planes parallel to the stems of the T's.

8. A falsework centering containing compound compression members for supporting a load, each of which members is composed of two pieces having major and minor dimensions transverse to their lengths, the two pieces being set together so that their combined cross section is approximately T shaped, a releasable connection between the two pieces, and sway bracing extending between compression members in planes parallel to the stems of the T's.

9. A falsework centering containing compound compression members for supporting a load, each of which members is composed of two pieces having major and minor dimensions transverse to their lengths, the two pieces being set together so that their combined cross section is approximately T shaped, and a releasable connection between the two pieces.

10. A falsework centering containing compound compression members for supporting a load, each of which members is composed of two pieces having major and minor dimensions transverse to their lengths, the two pieces being set together so that their combined cross section is approximately T

shaped with the cross of the T longer than the stem thereof, and a releasable connection between the two pieces.

11. A falsework centering containing compound compression members for supporting a load, each of said members being composed of a plurality of pieces having major and minor dimensions transverse to their lengths, the major dimension of one piece being ar- 10 ranged transversely to the major dimension of another piece, and a tie-wire uniting the pieces of each compression member.

12. A falsework centering containing compound compression members for supporting a load, each of which members is composed of two pieces having major and minor dimensions transverse to their lengths, the two pieces being set together so that their combined cross section is approximately T 15 shaped, and a tie-wire joining the two pieces. 20

13. A falsework centering for a bridge comprising compound columns for supporting a load and each consisting of a plurality of releasably interconnected longitudinal pieces, one of said pieces being wider than another of said pieces and arranged with its wider dimension parallel to that of similar pieces of other columns, and sway bracing attached to said columns and transverse to the wider dimensions of such wider pieces. 25 30

In witness whereof, I have hereunto set my hand and seal at Indianapolis, Indiana, this twentieth day of May, A. D. one thousand nine hundred and twelve.
